UNITED STATES PATENT OFFICE.

OTTO PLETSCHER, OF ALBISRIEDEN, SWITZERLAND.

ELECTRIC POCKET LAMP.

1,403,107.

Specification of Letters Patent. Patented Jan. 10, 1922.

Application filed October 27, 1917. Serial No. 198,853.

To all whom it may concern:

Be it known that I, Otto PLETSCHER, a citizen of the Republic of Switzerland, residing at Albisrieden, Canton of Zurich, Switzerland, have invented certain new and useful Improvements in Electric Pocket Lamps; and I do hereby declare the following to be a full, clear, and exact description of the invention, such as will enable others skilled in the art to which it appertains to make and use the same, reference being had to the accompanying drawing, and to letters or figures of reference marked thereon, which form a part of this specification.

It is known that in electric pocket lamps, the current for which is supplied by a hand-driven dynamo, it is necessary to have, for instance, a spring mechanism for the purpose of rendering the driving of the dynamo as uniform as possible, and of obtaining light even when the reciprocating winding movement has ceased. The reason that such an auxiliary device has been required, was that it was impossible to make the rotating part of the dynamo heavy enough to utilize it as a fly-wheel that would render the working and the running of the dynamo sufficiently uniform, since it was considered necessary, in connection with the driving, to arrange the spindle of the dynamo in the direction of the width of the pocket lamp. As however the pocket lamp had to be seized and held with one hand, whilst the same hand operated the dynamo, the width of the pocket lamp, and therefore the length of the dynamo, measured in its axial direction, were also limited.

This invention relates to an electric pocket lamp in which no auxiliary device is required for rendering the driving or running of the dynamo uniform, and the width of the pocket lamp forms no limitation for the length of the dynamo, measured in its axial direction. In the lamp according to this invention, the longitudinal axis of the dynamo is situated in the longitudinal direction of the pocket lamp casing, the dynamo has a field magnet acting as a fly-wheel, and the said field magnet can be rotated by means of a bevel gear at one end of the casing by means of a lever movable towards the latter and rotatable about a pin normal to the longitudinal direction of the casing, while the incandescent lamp is connected to the stationary armature.

A preferable construction is to make the

casing cylindrical and to provide it at the bottom with a projecting part at one side in which is arranged the driving means for the field magnet, the driving lever being also arranged at the bottom part of the casing at the side opposite the projecting part, so that the latter, when the lever is operated with the thumb, offers a support against any change of position of the casing in the hand.

A construction according to this invention is illustrated, by way of example, in the accompanying drawing, in which:

Fig. 1 shows the same in side elevation; 70

Fig. 2 is a longitudinal section;

Fig. 3 is a bottom view, with the cover removed;

Fig. 4 illustrates a section on the line II—II of Fig. 2; 75

Fig. 5 shows a section on the line I—I of Fig. 1, and

Fig. 6 is a section on the line III—III of Fig. 2.

An armature 1 has an iron core 2 of I-shaped cross-section and of bar-shape provided with a winding 3. At each end of the said armature is secured an end plate 4, the upper one of the said plates being provided with a hollow pin 6, through which one of the two ends 15 of the winding is carried to a terminal 18, the bottom plate being provided with a pin 5 resting in a plate 7. The latter is secured to a widened part 19 of the cylindrical casing 10. The hollow pin 6 has a square end mounted in a plate 7^a secured to the upper part of the cylindrical casing 10. This upper part is covered by a cap 9 carrying the incandescent bulb 20 with a lens 21 in front of it. The bulb is supplied with current through the other wire 15 which leads to a spring-controlled tongue 22 insulated from, and secured to the upper plate 7^a by a terminal 17. On the pin 5 is rotatably mounted at one side of the lower plate 7 a pinion 23 engaging with a toothed wheel 24 mounted between the casing itself and a bracket 25 secured to the plate 7. On the same spindle as the toothed wheel 24, is also mounted a pinion 26 engaging with a toothed wheel 27 mounted so as to rotate loosely, by means of a sleeve, on the pin 5 at the other side of the plate 7. On the outer circumference of the said sleeve rotates a ratchet wheel 28 provided with a bevel wheel 29. The spring-controlled pawl 35 of the ratchet wheel is on

the contrary secured to the toothed wheel 27. With the bevel wheel 29 engages a bevel wheel segment 30 secured to a lever 31 rotatable about a pin 32 and held in contact 5 with the casing 10 by means of a locking button 34 in opposition to the action of a spring 33. When the button 34 is turned, out of the position shown in Fig. 1, through an angle of 90°, the lever 31 will be released, 10 and the spring 33 will bring it into the dotted position shown in Fig. 1.

The pinion 23 is secured to a disc 8 secured to the lowest pair of magnets of a series 11 by means of screws. The upper 15 pair of magnets 11 is in its turn connected to a disc 8^a provided with a neck which is rotatably mounted about the cylindrical portion of the pin 6. The magnets of each pair are secured with their poles of the 20 same sign to the same pole piece 14, but the poles of the same sign leave between them an interval 13 (Figure 4). The object of the ring on the lever 31 is to facilitate the manipulation of the lever; thus for a short 25 thumb the position shown on the drawing will be used, and for a longer thumb the ring will be folded upwards towards the button 34.

In order to light the bulb of the pocket 30 lamp, the button 34 is turned through 90°, so that the lever 31 springs into the dotted position in Figure 1. The lamp is then surrounded by the four fingers, whilst the thumb is placed on the lever 31. By pressing 35 with the thumb on the lever 31, the latter is moved towards the casing 10, the segment 30 turns the wheel 27, and the latter turns the pinion 26 together with the wheel 24 which latter, by means of the pinion, 40 rotates the field magnet 11 with a rate of transmission of 1-20, in round figures. The lever is thereupon allowed to return to its initial position under the action of the spring 33, the ratchet wheel sliding along the pawl 45 35 so that the other wheels are not affected by the return movement of the lever. On the lever 31 being again operated, the field magnet will be again given an impulse for revolving. As the field magnet is approximately of the same length as the cylindrical portion of the casing 10, the whole of it 50 will act as a fly-wheel which provides for uniformity in running and drying. The comparatively considerable length of the field magnet results in a large number of 55 lines of force flowing from one pole piece to the other, and as the armature is mounted

within the field magnet and is of approximately the same length, a great number of windings on the armature can be intersected 60 by a great number of lines of force, held compactly together, and consequently the current generated produces a very strong illuminating power of the pocket lamps.

As the casing is cylindrical and provided 65 at the bottom with a portion widened to one side in which is mounted the driving means for the field magnet, and as the driving lever is at the opposite side to said portion, the latter, during the operation of the lever 70 with the thumb, offers a hold against any change of position of the casing in the hand. The arrangement of the driving means in the lower portion of the casing, that is to say, in the widened portion, allows of 75 using a high rate of transmission.

What I claim is:

1. An electric pocket lamp comprising a casing, a stationary armature therein, an electric lamp connected thereto, a rotatable 80 impulse driven field member having a large mass, exterior of said armature and whose inertia will be maintained substantially constant during the interval between successive impulses, and hand-operated impulse mechanism for driving said field member. 85

2. An electric pocket lamp comprising a casing, a stationary elongated armature in said casing, an electric lamp connected to said armature, a cylindrical elongated field 90 member rotatably mounted within said casing and around said armature, and an impulse mechanism mounted in an enlarged portion of the casing at the end of said armature and field member. 95

3. An electric pocket lamp comprising a tubular body portion having an eccentric enlargement at one end, a stationary armature mounted in said tubular portion, and a tubular rotatable field member within the 100 casing surrounding said armature, an impulse gear train, in said enlargement for imparting high velocity to said field member and a thumb lever for actuating said gear train, said field member having sufficient mass to maintain substantially uniform speed between successive impulses produced by said lever and thereby maintain uniform illumination, and said casing enlargement forming a grip to securely hold the casing 110 during operation of said lever.

In testimony that I claim the foregoing as my invention, I have signed my name.

OTTO PLETSCHER.
